UNITED STATES PATENT OFFICE.

HUBERT S. TURNER, OF BROOKLYN, NEW YORK.

TELEPHONE SYSTEM.

Original application filed February 27, 1915, Serial No. 11,046. Divided and this application filed February 6, 1923. Serial No. 617,239.

To all whom it may concern:

Be it known that I, HUBERT S. TURNER, a citizen of the United States of America, residing at Brooklyn, in the county of Kings 5 and State of New York, have invented certain new and useful Improvements in Telephone Systems, of which the following is a full, clear, concise, and exact description.

This invention relates to telephone systems 10 and more particularly to such systems in which connections between subscribers' lines are established by means of cord and trunk circuits. This application is a division of application, Serial No. 11,046, filed February 27, 1915, Patent No. 1,451,896, April 17, 1923.

In telephone systems where connections between subscribers' lines are established by means of operator's cord and trunk circuits, 20 a calling subscriber, having initiated a call, may hang up his receiver before the called subscriber answers, either due to the failure of the called subscriber to answer quickly enough, or due to the abandonment of the 25 call by the calling subscriber. In such a case where a call is abandoned, it is unnecessary to continue the ringing of the called subscriber's line.

Heretofore in systems of this nature, if the 30 operator at the A or answering switchboard, or the operator at the B or trunk switchboard is slow in taking down the connection in the case of an abandoned call, ringing current would continue to flow over the 35 called-for line and this line would be inaccessible to other incoming calls until the connection had been taken down, and the called subscriber may be delayed in extending a call from his station.

40 One of the objects of this invention is, therefore, to enable the calling subscriber to control the disconnection of the machine ringing from the called line in systems where the connection between the calling and called lines is built up over a cord and a trunk circuit.

Another object of the invention is to free 50 a called line for further incoming calls and for outgoing calls in systems wherein the calling and called lines are interconnected over cord and trunk circuits as soon as the subscriber at the called line restores his receiver to the switchhook.

The above and other objects are obtained

according to one feature of this invention 55 by the provision of cord and trunk circuits wherein a ringing relay is deenergized by the replacement of the receiver on the switchhook at a calling substation to automatically disconnect a ringing current source from the 60 cord circuit thereby discontinuing the flow of ringing current over the called line.

Another feature of this invention resides in the provision of trunk relays which are controlled by the aforesaid ringing relay and which in turn control the cut-off relay of a 65 called line so that when a calling subscriber restores the receiver to the switchhook, the deenergization of the ringing relay effected thereby, causes the deenergization of the 70 trunk and cut-off relays, thereby restoring the line signal of the called line to the control of the called subscriber and removing the busy potential from multiple jacks associated with the line. 75

The invention will be readily understood from the following detailed description and by reference to the accompanying drawing, in which Fig. 1 shows a subscriber's line and an operator's cord circuit embodying features of this invention; Fig. 2 shows the means employed in making busy tests; Figs. 3, 4 and 5 show three different forms of 80 trunk circuits which embody features of this invention and are adapted to cooperate with 85 the cord circuit shown in Fig. 1 in completing connections between calling and called subscribers. Fig. 6 shows an alternate form of a portion of the modification shown in 90 Fig. 5.

Referring first to Fig. 1, 1 represents a telephone substation which includes a telephone receiver 2, a transmitter 3, a switchhook 4, a call bell 5, a condenser 6, and primary 7 and secondary 8 of an induction 95 coil. The elements 3 and 7 are included in a bridge of the telephone line, which is open when the telephone receiver is upon the switchhook 4 and which is closed by the switchhook 4 when relieved of the weight of 100 the telephone receiver. The elements 5 and 6 are included in another bridge permanently continuous with respect to alternating currents, but non-continuous with respect to direct currents. The type of substation outfit shown is one that I have selected for the purpose of illustrating the invention, but it is to be understood that I do not 105

limit myself to the form of substation apparatus shown, for it will be seen as the description of the invention is proceeded with, that the operation of the system does not depend upon the particular substation outfit shown. Substation 1 is connected to the exchange in the form of the invention shown by means of metallic circuits, whose limbs 9 and 10 are connected with the line springs or talking contacts of spring jacks 11 and 12. A plurality of spring jacks is shown in multiple relation with each line, the lower-most spring jack 12 constituting the answering jack, while the remaining jacks, such as 11, constitute multiple jacks. The limbs 9 and 10 also terminate in contacts on the right and left armatures of cut-off relay 13, the limbs of each telephone line being normally connected by means of said armatures and the contacts normally engaged thereby with a line relay 14, the limb 9 being connected with the left hand winding and the limb 10 being connected with the right hand winding of said relay, the other terminals of the windings of said relay being connected through grounded battery 15. Line relay 14 is actuated by the removal of the telephone receiver at substation 1 from its supporting switchhook by means of a circuit which may be traced as follows: from transmitter 3, through line 9, left hand armature and normal contact of cut-off relay 13, left hand winding of line relay 14 to the live pole of grounded battery 15, through said battery to ground, through resistance 16, right hand winding of line relay 14, right hand normal contact and armature switch of cut-off relay 13, line 10, primary 7, switchhook 4, completing the circuit through transmitter 3. This actuation of line relay 14 causes its armature to close a circuit through line lamp or signal 17 which may be traced from ground, through said resistance 16, said armature and front contact of line relay 14, line lamp or signal 17, interrupter 18 and its brush through battery 15 to ground. Interrupter 18 consists of a rotating metallic member with one or more insulating segments, there being a shunt circuit around said interrupter through resistance 19. Hence, the current passing through resistance 16, from line lamp or signal 17 is a variable one though not intermittent and the current from grounded battery 15 passing through the same resistance to the described line circuit including primary 7 is also made variable thereby. This variable current sets up an alternating current in secondary 8 which is heard as an audible signal in the telephone receiver 2 which is in circuit with said secondary. It will be seen that if the circuit was open through limbs 9 and 10, there would be no path for the described variable current and hence no audible signal would be produced; and if the circuit

was open through line lamp or signal 17, the current passing through resistance 16 would not be a variable one and no audible signal would be produced. Therefore the production of the audible signal in the receiver 2 is an assurance to the party at substation 1 that the line wires are in working condition and that the line lamp or signal at the central exchange has been displayed.

Having observed the displayed line lamp or signal 17 of the calling substation, the operator inserts answering plug 20 into answering jack 12 corresponding to the calling substation. This action closes a circuit which may be traced as follows: From the grounded terminal of cut-off relay 13, through the winding of said relay, sleeve of answering jack 12, sleeve contact of answering plug 20, left hand winding of answering supervisory relay 21, winding of operator's relay 22, armature and back contact of controlling relay 23 to the live pole of grounded battery 15, completing the circuit through the same. The actuation of cut-off relay 13, due to the current flowing through the traced circuit, breaks the circuit from substation 1 through line relay 14, and line lamp or signal 17 therefore resumes its normal condition due to the consequent disengagement of the armature of line relay 14 from its contact. The actuation of operator's relay 22 due to the current flowing through the same traced circuit causes its various armatures to be attracted.

The actuation of answering supervisory relay 21 due to the current flowing through the circuit just traced closes another circuit which may be traced as follows: from ground, through battery 15, talking interrupter 24, front contact and armature of actuated answering supervisory relay 21, winding of answering relay 25, sleeve contact of answering plug 20, sleeve of answering jack 12, and winding of cut-off relay 13, completing the circuit to ground. The actuation of answering relay 25 due to the current flowing through the circuit just traced causes its various armatures to be attracted.

A circuit may then be traced as follows: from ground, through repeating coil winding 26, uppermost armature and front contact of the two top ones of answering relay 25, ring contact of answering plug 20, ring contact spring of answering jack 12, limb 9, transmitter 3, switchhook 4, primary 7, limb 10, tip spring of answering jack 12, tip contact of answering plug 20, right hand winding of answering supervisory relay 21 and the non-inductive resistance in multiple relation thereto, lowermost front contact and armature of the three bottom ones of answering relay 25, repeating coil winding 27, and grounded battery 15, completing the circuit to ground. The current thus al-

lowed to flow through the right hand winding of answering supervisory relay 21 is sufficient to maintain its armature disengaged from its normal contact when current ceases to flow through the left hand winding.

At the same time, primary 7 at substation 1 receives operating current from grounded battery 15, and receiver 2 is placed in inductive relation with windings 26 and 27 of the repeating coil. Therefore, the party at substation 1 is telephonically connected with the operator who has responded to the line signal, as the actuation of operator's relay 22 connects the operator's telephone receiver 28 to the line of the calling substation. A circuit for this connection may be traced as follows: from ground through repeating coil winding 26, through the front contact and uppermost armature 29 of the two top ones of operator's relay 22, secondary of operator's induction coil 31, receiver 28, condenser 32, bottom armature and front left hand contact of operator's relay 22, repeating coil winding 27 and grounded battery 15, completing the circuit to ground.

When cut-off relay 13 actuates, simultaneously with the actuation of answering supervisory relay 21, and operator's relay 22, the audible signal in receiver 2 at substation 1 ceases, as limbs 9 and 10 were disconnected from the variable current flowing through resistance 16. The cessation of this audible signal may be used as a notification to the party at substation 1 that an exchange operator is connected to his line and is ready to receive the number of the line he wishes to be connected to, as answering relay 25 is actuated as soon as supervisory relay 21 is actuated, thereby completing a telephonic connection between the called party and the answering operator. Therefore the usual verbal inquiry of the operator may be dispensed with. However, the operator may converse with the calling party, if desired or if necessary, by means of operator's transmitter 33 and primary 34 of the operator's induction coil.

Having been informed as to the number of the line that the calling party desires connection with, the A operator communicates with the B operator over a call wire (not shown). The B operator informs the A operator as to the number of the trunk taken for use and then tests the called line. The busy test for the trunk line shown in Fig. 3 is not made with the tip of the trunk plug 254, as is usually the case, but is made by the use of apparatus illustrated in Fig. 2, wherein 245 represents a metallic thimble of any convenient form adapted to be worn on the end of one of the fingers of one or both of the hands of the B operator. Previous to inserting trunk plug 254 into a multiple jack, the sleeve of said jack is touched by

thimble 254 and if the same is at a potential above that of the earth (as is the case when a busy line is tested), the current flowing to ground through primary 246 which is connected to thimble 245 induces current 70 in secondary 247 which is connected to the B operator's telephone receiver. Secondary 247 is preferably of a high resistance so as not to impede the voice currents from the A operator's set which pass from the lines 75 248 and 249 to said B operator's receiver. After testing the called-for line and having found it idle, the B operator inserts plug 254 into the multiple jack 211.

The A operator after receiving the number of the assigned trunk from the B operator inserts calling plug 35 into jack 255 thereby establishing a circuit traceable as follows: from ground, through the sleeve of jack 255, sleeve contact of calling plug 35, spring switch 38 and back contact of calling relay 39, winding of ringing relay 40, right and left hand contacts connected by the bottom armature of actuated operator's relay 22 and winding 27 of the 90 repeating coil, completing the circuit through grounded battery 15. Ringing relay 40 is energized in this circuit and its various armatures are attracted. The engagement of the top armature of relay 40 with its two contacts closes two circuits first, and then operates spring switches 42, 43 and 44 afterwards. The two bottom armatures of relay 40 are not attracted until after the engagement of the top armature has 100 taken place. The circuits may be traced as follows: first from the upper terminal of the winding of relay 40, through the armature and the left hand front contact thereof, upper winding of controlling relay 23, 105 spring switch 42 (which is disengaged from its normal contact), spring switch 43 (which is in turn disengaged from its normal contact), middle one of the three bottom armatures and engaged contact of answering relay 25, ringing interrupter 45 and grounded battery, completing the circuit through the circuit already traced to ground at the sleeve of jack 255. The second circuit may be traced from the grounded terminal of magnetic clutch 46 of party line ringing key 47, release key 48, the winding of said clutch, supervisory lamp 49, right hand front contact and top armature of ringing relay 40, and the left hand front contact of the same completing the circuit through the circuit already traced through the upper winding of controlling relay 23 and ringing interrupter 45. The current 115 thus allowed to flow through said winding energizes relay 23 and its armature disengages its contact, opening the circuit through the winding of operator's relay 22 and left hand winding of answering supervisory relay 21. The consequent deenergiza-

120
125
130

tion of operator's relay 22 releases its various armatures, removing the operator's telephone set from telephonic connection with the calling substation and opening the energizing circuit of ringing relay 40, which has been traced from the upper terminal of the winding of said relay through the two contacts of the bottom armature of operator's relay 22. However, current still flows through the winding of ringing relay 40 to maintain the same actuated by way of the circuit traced through the upper winding of controlling relay 23.

With plug 35 inserted into jack 255 and with relay 40 operated, ringing current is now connected to the trunk circuit and relay 250 is operated over a path extending from ground through ringing machine 59, interrupters 89 and 78, normal contact and spring switch of key 51, alternate contact of the inner lower armature of relay 40, non-inductive resistance 63, normal contact and left spring switch of key 54, normal contact and right spring switch of key 53, tips of plug 35 and jack 255, winding of relay 250, rings of jack 255 and plug 35, left spring switch and normal contact of key 53, right spring switch and normal contact of key 54, winding 29 of the repeating coil, spring switch 44 and engaged contact of ringing relay 40, spring switch and normal contact of key 56, completing the circuit to ground. Since the return path for ringing current is through the winding 29 of the repeating coil and since the operator's receiver 2 is inductively connected to the winding 29 of the repeating coil, the calling subscriber as well as the called subscriber, will receive an audible signal as long as ringing current is applied to the trunk circuit.

Relay 250, in operating, closes a circuit which may be traced as follows: from grounded battery 252, through the armature and front contact of trunk relay 250, trunk ringing supervisory lamp or signal 253 and sleeve contact of trunk plug 254, completing the circuit to ground through the cut-off relay 210 when plug 254 is inserted in the multiple jack 211. The cut-off relay 210 and the trunk ringing supervisory lamp or signal 253 are both energized by the current flowing in this circuit.

If a single party station, such as station 500, is being called, ringing current for signaling said station will be impressed upon the called line over a circuit extending from tip spring of jack 255, spring switches 256 and 257 of relay 258, winding of relay 251, tip contacts of plug 254 and jack 211, the called substation bell or annunciator, ring contacts of jack 211 and plug 254, spring switch 259, normal contact of relay 258 and ring spring of trunk jack 255, completing the circuit through the A board ringing devices over the path previ-

ously described. Trunk supervisory relay 251 is energized by the current flowing in this circuit.

The cord circuit shown in Fig. 1, is provided with the necessary equipment for party line ringing. It will be understood that there may be a number of stations, such as 500, bridged across the line leading to the multiple jack 211. If a party line station is desired, the operator will depress a key in the cord circuit corresponding to the particular station of the party line desired. The paths for the ringing current when party line ringing is employed, is fully described in the aforementioned application. Assuming, for example, that a party corresponding to the key 51 is desired, the operator will actuate key 51, whereupon a circuit for ringing current may be traced as follows: from ground, through ringing generator 59, interrupter 60, brush 61, interrupter 62, and its associated brush, upper alternate contacts of key 51, alternate contact and engaged uppermost armature of the two bottom ones of ringing relay 40, non-inductive resistance 53, normal contact and left spring of key 54, normal contact and right spring of key 53, tip contact of calling plug 35 and thence over the path previously traced from the trunk circuit and the called substation loop, through the ring contact of plug 35, left hand spring 53 and its normal contact, right hand spring 54 and its normal contact, conductor 47, winding 29 of the repeating coil, spring switch 44 and front contact of relay 40, spring switches 55 and 56, to ground. Trunk supervisory ringing key 251 is also energized by current flowing in this circuit.

When the called substation responds, the high resistance winding of trunk relay 250 is shunted by the low resistance path formed at the called substation and its armature disengages its alternate contact and reengages its normal contact, thereby extinguishing trunk ringing supervisory lamp 253. The closing of the low resistance circuit causes the actuation of the calling relay and the de-energization of the ringing relay both located at the A board. Current from the repeating coil of the link connector now flows through the trunk circuit. As trunk supervisory relay 251 is in series with the substation circuit, it remains actuated and when the armature of trunk relay 250 reengages its normal contact, the circuit through the sleeve contact of trunk plug 254, which was opened by the disengagement of said armature from its alternate contact, is closed again but this time through the winding of connecting relay 258 instead of lamp 253. This circuit may be traced as follows: from ground, through the winding of cut-off relay 210, sleeve of the multiple jack 211, sleeve contact of plug 254, winding of con-

necting relay 258, armature and front contact of trunk supervisory relay 251, normal contact and armature of trunk relay 250 and grounded battery 252, completing the circuit 5 to ground. Due to the current flowing in this circuit, both the cut-off relay 210 and connecting relay 258 are actuated. The engagement of the top armature switch of relay 258 and of spring 259 establishes a 10 ground connection through the winding 260 of the repeating coil to the ring contact of the trunk plug 254 previous to disengaging said spring switch from its normal contact, thereby breaking the connection from said 15 ring contact to ground through the ring spring of trunk jack 255 and the repeating coil associated with the link connector at the A board. The engagement of the bottom armature of relay 258 with spring switch 257 20 establishes a connection from the live pole of grounded battery 252, through winding 261 of the repeating coil to the tip contact of the trunk plug, previous to disengaging said spring switch from spring switch 256, 25 thereby opening the connection from the tip contact to the live pole of the grounded battery 15 through the tip spring of trunk jack 255 and the repeating coil associated with the link connector at the A board. 30 In this manner, relay 251 is maintained actuated, though the source of energizing current has been changed from the repeating coil at the A board to the repeating coil associated with the trunk circuit. As the 35 top and bottom armatures of connecting relay 258 connect current of the same polarity to the tip and ring contacts of trunk plug 254 as that connected thereto through the tip and ring springs of trunk jack 255, it is immaterial whether the armatures engage their 40 respective spring switches simultaneously or not.

When the bottom armature of connecting relay 258 disengages spring switch 257 from 45 spring switch 256, it engages the former with its alternate contact, and thereby bridges non-inductive resistance 262 across the inductive winding of trunk supervisory relay 251, allowing voice currents to pass 50 said relay. At the same time, spring switch 256 has been allowed to engage its alternate contact, thereby closing a circuit which may be traced as follows: from the tip spring 55 of trunk jack 255, through said spring 256 and engaged alternate contact, windings 263 and 264 of the repeating coil, ring spring 60 of trunk jack 255 and thence over the talking conductors of the calling link connector at the A board, completing the circuit back 65 to said tip spring. The high resistance winding of trunk relay 250 is, therefore, shunted by the lower resistance and lower impedance path furnished by windings 263 and 264 of the repeating coil and there- 70 fore, the voice currents from the repeat-

ing coil at the A board pass through said windings 263 and 264. The trunk relay 250 is not actuated by the current from said A board repeating coil due to the low resistance shunt formed by the windings 263 and 264. As the called substation is now directly connected to windings 260 and 261 of the repeating coil, conversation can be carried on through the connected substations. The engagement of the uppermost of the 75 two bottom armatures of connecting relay 258 with its right hand contact closes a circuit from grounded battery 252, through talking supervisory lamp or signal 265 which is thereby energized, and its engagement with its left hand contact short circuits the upper half of the winding of connecting relay 258, the purpose of this short circuit being, as described in the aforementioned application, to furnish means for preventing an accidental or deliberate connection to a busy line. 80 This short circuit also furnishes current from grounded battery 252 to the lower half of the winding of the connecting relay 258 85 independent of the armature of supervisory relay 251, so that a momentary disengagement of this armature does not deenergize the connecting relay. 90 When the telephone receiver of the called 95 subscriber is replaced upon its switchhook, the circuit through supervisory relay 251 is opened and, therefore, its armature switch reengages its contact which is connected to the sleeve contact of trunk plug 254. 100 Therefore, the current from grounded battery 252 flowing through the uppermost one of the two bottom armatures and the engaged left hand contact of connecting relay 258 now has two paths offered to it, from 105 the central terminal of the winding of said relay toward both ends of the same, and as these windings are in opposition to each other, the connecting relay is consequently deenergized, restoring the other connections 110 controlled by said relay to their normal condition. The circuit through the sleeve contact of trunk plug 254 being opened by the deenergization of the connecting relay 258, the cut-off relay 210 associated with the 115 called line is deenergized and the control of the line relay 503, and the line lamp or signal 501 of the called line is restored to the control of the called substation. The disengagement of spring switch 256 of connecting relay 258 from its alternate contact when said relay 258 was deenergized, 120 opened the circuit through the windings 263 and 264 of the repeating coil. Therefore, the low resistance shunt around the high 125 resistance winding of trunk relay 250 is removed and as the current, flowing through said windings, is not sufficient to maintain actuated the calling supervisory relay associated with the link connector at the A 130

board which is connected to trunk jack 255, said calling supervisory relay 50 is deenergized and said link connector circuit opened.

If the telephone receiver of the calling station had been replaced before the called party answered, relay 21 would have deenergized due to the opening of its circuit at the calling substation. At this time answering relay 25 is actuated as hereinbefore described and a circuit is closed which has not been previously described. This circuit may be traced as follows: from the live pole of grounded battery 15, through talking interrupter 24, uppermost one of the three bottom armature switches and front contact of answering relay 25 to the center terminal of the winding of said relay through the upper portion of said winding, sleeve contact of answering plug 20, sleeve contact of answering jack 12 and winding of cut-off relay 13, completing the circuit to grounded battery 15. This circuit short circuits the lower half of the winding of answering relay 25 which received current from interrupter 24, in the first place, through the alternate contact and armature of answering supervisory relay 21. With relay 21 deenergized as first described the current from interrupter 24 now has two paths leading from the central terminals of the winding of answering relay 25, one toward the upper terminal of said winding and thence to sleeve contact of plug 20 and one towards the bottom terminal of the winding of relay 25 and thence through the armature and normal contact of answering supervisory relay 21 to the sleeve of plug 20. As these two windings are opposed to each other, relay 25 becomes deenergized and its various armatures disengage their respective contacts. One of the objects in arranging for such a deenergization of relay 25 is on account of the sensitive action inherent in supervisory relays which are inserted in the talking circuits. A momentary disengagement of the armature of answering supervisory relay 21 from its alternate contact will not release answering relay 25 due to the shunt circuit around the armature, it being necessary for said armature switch to fall all the way back and engage its normal contact before said relays can be affected. Current is thereby cut off from the tip, ring and sleeve contacts of answering plug 20 and therefore cut off relay 13 is deenergized, its armatures engaging their contacts thereby restoring line relay 14 and line lamp or signal 17 to the control of the apparatus at substation 1.

It will be seen therefore that it is immaterial whether answering plug 20 is removed or not from answering jack 12, as the three strands of the link connector are all open and from an operating standpoint there is no connection from the jack to the link connector. As long as calling plug 35 remains

connected to the jack 255, controlling relay 23 remains actuated thereby maintaining the circuit open from cut off relay 13 through the left hand winding of answering supervisory relay 21 and operator's relay 22. The restoration of the receiver to the switchhook at the calling substation previous to the response of the called substation also causes the deenergization of the ringing relay 40 of the link connector engaged with the trunk jack 255. The deenergization of relay 40 opens the circuit through the tip and ring springs of jack 255, thereby causing the deenergization of trunk relay 250 and trunk supervisory relay 251 and consequently, the circuit through trunk ringing supervisory lamp 253 and the sleeve contact of trunk plug 254 would also be opened. Therefore the cutoff relay 210 would have deenergized and the line relay 503 and the line lamp 501 would be restored to the control of the called subscriber at substation 500. The line would test idle at any multiple jack associated therewith and the subscriber could initiate calls.

The calling link connector at the A board, the trunk circuit and the called line are all released for further connections by the replacing of the telephone receiver at the called substation on its switchhook. Connections can be made from the released called substation regardless of the connection to a multiple jack associated with said line of the trunk plug of the released trunk circuit and the line will test idle at any multiple jack as the only connection from the tip and ring springs of said line, through said released trunk circuit, is through the winding of trunk supervisory relay 251 in series with the high resistance winding of relay 250. As this latter winding is not only of high resistance but high impedance as well, the line lamp of the connected line is not energized thereby, nor are voice currents from the connected line allowed to pass through said winding.

The embodiment of the invention shown in Fig. 3 is preferably intended for use where the outgoing trunk calls are handled by a single operator. Where more than one operator handles the outgoing calls, ringing current might be impressed upon a line with which a released trunk circuit was connected and said ringing current, passing through the ring and tip contacts of the released trunk circuit, would actuate relays 250 and 251. Therefore, when more than one operator handles the outgoing calls at the B board, the embodiment of the system illustrated in Fig. 4 is preferable.

In Fig. 4, trunk relay 266 corresponds to trunk relay 250 in Fig. 3, and it actuates as has been described in relation to said Fig. 3, excepting that the upper terminal of the winding of trunk relay 250 was con-

needed to ground through the ring spring of trunk jack 255 and the repeating coil of the link connector at the A board, while the upper terminal of trunk relay 266, Fig. 4, is connected direct to ground at the B board. This is done only if waiting connections are to be made through the trunk circuit. If the waiting connections are used and this ground connection was made through the repeating coil at the A board then the calling subscriber would receive a false ringing audible signal through the substation telephone receiver, due to the ringing current flowing through trunk relay 266 to maintain its actuation while the trunk link connection is in the waiting condition.

On receiving a call from the A operator over a call wire circuit (not shown), the B operator tests the called-for line, such as that shown at the right of Fig. 3, by engaging the tip of plug 268 with the sleeve of jack 211 associated with said line and, if the line tests idle, inserts the plug into said jack. The engagement of the armature of trunk relay 266 with its alternate contact, due to the flow of ringing current therethrough in manner similar to that previously described, allows current from grounded battery 269 to flow through trunk ringing supervisory lamp or signal 270, which energizes the same. The insertion of plug 268 into the jack 211 closes a circuit which may be traced as follows: from ground, through the cut-off relay 210, sleeve of jack 211, sleeve contact of calling plug 268, resistance 271, top armature and normal contact of trunk controlling relay 272, winding of trunk ringing relay 273, spring switch 274 and normal contact of said relay, waiting interrupter 275 and grounded battery 269, completing the circuit to ground. The cut-off relay 210 and trunk ringing relay 273 are both energized by the current flowing through this circuit whereupon a circuit is closed for the ringing current from the tip and ring springs of trunk jack 267 which may be traced as follows: from the ring spring of jack 267, through the contact and engaged middle one of the three top armature switches of trunk relay 273, ring contact of trunk plug 268, substation call bell or annulator, tip contact of plug 268, right hand winding of trunk supervisory relay 276, lowermost one of the two bottom armatures of trunk ringing relay 273, its engaged contact and the tip spring of trunk jack 267, completing the circuit to the ring spring through the ringing devices associated with the link connector engaged with trunk jack 267 at the A board as described in connection with Fig. 3.

The engagement with its contact of the lowermost one of the three top armatures of trunk ringing relay 273 closes a shunt circuit around resistance 271 which may be

traced as follows: from the right hand terminal of resistance 271, inner lower armature and normal contact of trunk calling relay 277, armature and front contact of trunk ringing relay 273, upper winding of trunk controlling relay 272, normal contact and top armature switch of relay 272, completing the shunt circuit to the left hand terminal of resistance 271. The current flowing through said shunt circuit is sufficient to cause the actuation of trunk controlling relay 272 and when its top armature disengages its normal contact, the circuit is opened through resistance 271 and all the current flowing through the sleeve contact of trunk plug 268 and the winding of trunk ringing relay 273, now flows through the upper winding of trunk controlling relay 272.

The engagement of the uppermost one of the two bottom armatures of trunk ringing relay 273 with spring switch 274 connects the lower terminal of the winding of said relay direct to grounded battery 269 before the disengagement of said spring switch from its normal contact disconnects said terminal from the battery by way of waiting interrupter 275. The engagement of the spring switch 274 with its alternate contact short circuits a part of the winding of said relay, the purpose of which has been hereinbefore described in connection with Fig. 3.

When the called substation responds, trunk relay 266 is shunted by a low resistance path as has been hereinbefore described, and therefore its armature switch disengages its alternate contact, thereby extinguishing the ringing supervisory signal 270, and engages its normal contact, closing a circuit which may be traced as follows: from ground, through the cutoff relay 210 sleeve contact of trunk plug 268, winding of trunk calling relay 277, left hand winding of trunk supervisory relay 276, uppermost one and engaged contact of the three top armatures of trunk ringing relay 273, normal contact and armature of trunk relay 266 and grounded battery 269, completing the circuit to ground. Trunk calling relay 277 is energized by the current flowing through this circuit. Its uppermost and middle armatures and its two bottom armatures engage their respective contacts before the lowermost of the three top ones disengages its contact. The engagement of the middle one of the three top armatures with its contact connects the ring contact of trunk plug 268 to ground through winding 278 of the repeating coil and the engagement of the lowermost one of the two bottom armatures with its two contacts, bridges non-inductive resistance 279 across the right hand winding of trunk supervisory relay 276 and connects both to the live pole of grounded battery 269 through winding 280 of the repeating

coil. The engagement with its contact of the uppermost one of the three top armatures of calling relay 277 closes the circuit from the tip and ring springs of trunk jack 267 through windings 281 and 282 of the repeating coil. Therefore, the two substations are telephonically connected and conversation can take place between them as soon as trunk ringing relay 273 is deenergized which takes place when the lowermost one of the three top armature switches of calling relay 277 disengages its contact, thereby opening the circuit through the winding of trunk ringing relay 273. The engagement with its left hand contact of the uppermost of the two bottom armature switches of calling relay 277 closed a circuit through talking supervisory lamp or signal 283 and grounded battery 269, the energization of said lamp or signal being the operator's assurance that the called substation has responded. The engagement of said armature with its right hand contact had established a connection to the live pole of grounded battery 269 from the lower terminal of the winding of trunk calling relay 277 previous to the breaking of the other connection to the same through the left hand winding of trunk supervisory relay 276, when the uppermost one of the three top armature switches of trunk ringing relay 273 disengaged its contact. Trunk calling relay 277 therefore, remains actuated.

When the telephone receiver at the called station is replaced upon its switchhook, trunk supervisory relay 276 is deenergized and the engagement of its armature with its normal contact short circuits the winding of calling relay 277 which is thereby deenergized, opening the circuit through the sleeve contact of trunk plug 268, deenergizing the cut off relay 210 and thereby restoring the line relay 503 and line signal 501 to the control of the called substation. Therefore, the line will test idle at any multiple jack associated therewith. At the same time the disengagement from its contact of the uppermost one of the three top armatures of trunk calling relay 277, opens the circuit from the tip and ring spring of trunk plug 267 through windings 281 and 282 of the repeating coil, thereby removing the low resistance shunt from around the winding of trunk relay 266 and causing the calling supervisory relay associated with the link connector engaged with trunk plug 267 at the A board to be deenergized and said link connector circuit opened, as has been hereinbefore described in connection with Fig. 3.

When the busy test was made on the sleeve of the jack 211 of the called-for line, if the same had been busy, the sleeve would have been at a potential above that of the earth and current would have flowed

through the tip contact of trunk plug 268, non-inductive resistance 279, bottom armature switch and normal contact of trunk controlling relay 272 and special primary 284 of the operator's induction coil to ground. This would have caused a signal to be heard in the telephone receiver 285 on account of its connection to the secondary winding 286 of the induction coil. The secondary winding 286 of the induction coil is of a sufficiently high resistance and impedance as not to shunt the voice currents from lines 287 and 288 to any appreciable extent. When the busy test was made, if another connector had been engaged with the jack multiplied to the tested line and the same had been in the waiting condition, the signal produced in the telephone receiver 285 would have been distinctive to waiting interrupter 275.

The circuit for the current producing this signal may be traced as follows: from ground, through the primary 284, back contact and lower armature of relay 272, resistance element 279, tip contact of calling plug 268, sleeve of the multiple jack of the tested line, sleeve of the multiple jack associated with said line to which is connected the link connector impressing ringing current on said line, sleeve contact of the calling plug such as 268 associated with said link connector, resistance 271, upper armature and back contact of relay 272, winding of relay 273, spring 274 and normal contact through the interrupter 275 to ground through the battery 269. If said link connector had been in a ringing or talking condition, the signal in said receiver would have been in the nature of a click; as constant current from grounded battery 269 would flow through the primary winding 284 of the operator's induction coil.

When a connection is made to a busy line, trunk ringing relay 273 is prevented from fully actuating in the same manner as has been described in my aforementioned patent in relation to ringing relay 40 (Fig. 1).

However, the uppermost and lowermost ones of the three top armatures of relay 273 engage their respective contacts, though all the other armatures do not engage their respective contacts. Trunk controlling relay 272 is energized therefore, by the current flowing through its upper winding, and the disengagement of its armature switch from its contact prevents trunk ringing relay 273 from being energized again should the telephone receiver at the calling substation be replaced upon its switchhook previous to the response of the called substation.

Trunk controlling relay 272 has a lower locking winding which maintains said relay actuated as long as trunk plug 268 is inserted in a jack, its function and mode of operation being the same as that described in relation to controlling relay 23, Fig. 1.

In the event that the calling party replaces the receiver upon its switchhook previous to the response of a called party, the consequent engagement of the armature switch of trunk relay 266 with its normal contact would close the already described circuit through the engaged contact and uppermost one of the three top armatures of trunk ringing relay 273 and the left hand winding of trunk supervisory relay 276 and where a trunk calling relay 277 was consequently energized, the disengagement of the lowermost one of the three top armatures from its contact will deenergize relay 273, thereby deenergizing the left hand winding of trunk supervisory relay 276, and as the right hand winding of said relay would not be energized, (due to the fact that there is no closed circuit for direct current at the called substation which has not responded), its armature switch would engage its normal contact, thereby short circuiting the winding of trunk calling relay 277 and deenergizing the same. The same procedure would take place if the telephone receiver at the calling substation was replaced on its switchhook when ringing current was being impressed on the line. In both cases the called-for line is automatically restored to its normal idle condition.

The completion of the call when awaiting connection is made and the busy line is released, is the same as that described in relation to Fig. 1 in my aforesaid application. The engagement with its contact of the middle one of the three top armatures of trunk ringing relay 273 and the engagement with its contact of the lowermost one of the two bottom armatures of said relay, allows ringing current from the A board to be impressed upon the called for line and as the return path to ground for said current is through the grounded winding of the repeating coil associated with the link connector engaged with trunk jack 267, the calling party receives an audible signal in the substation telephone receiver which assures him that the substation call bell of the line he is waiting for has been released from its busy condition and is being rung upon. For party line ringing the proper ringing key is depressed or manipulated by the operator at the A board and ringing current is then sent out in the manner fully described in the aforesaid application.

In Figs. 5 and 6 I have illustrated a more complete embodiment of the adaptation of the system to trunk line work. In these embodiments the ringing current is furnished from either the A or B boards. In Fig. 5 I have shown the ringing current as being furnished from the B board and in Fig. 6, I have shown the connections to be changed from the showing in Fig. 5 if the

ringing current is furnished from the A 65 board.

As many features shown in Fig. 5 have already been amply described, mention will be made only of those features which differ from those illustrated in the preceding 70 figures.

When the A operator inserts the calling plug in the trunk jack 289, a circuit for the ringing current is closed which may be traced as follows: from the tip spring of trunk jack 289, through the lower winding of trunk relay 290 (which is of low resistance), spring switch 291 and normal contact of trunk calling relay 292 and upper winding of trunk relay 290 (which is of high resistance), completing the circuit to ground and therefore to the grounded terminal of the ringing generator associated with the A board. During the interval between the impression of alternating current on this circuit, the intermittent, direct current from the battery interrupter 91 in Fig. 1 is impressed upon the same circuit and trunk relay 290 is actuated by both of said currents as are the trunk relays illustrated in the preceding figures. The actuation of trunk relay 290 which is similar to the described trunk relays illustrated in the preceding figures, closes a circuit from grounded battery 293, through trunk ringing supervisory lamp or signal 294. This lamp or signal is energized by the current flowing through this circuit, its energization always indicating that the called line has not responded. The busy tests are made in the same manner as described in relation to Fig. 4.

When the trunk plug 295 is inserted in a multiple jack such as 211, a circuit is closed which may be traced as follows: from ground, through the cut-off relay 210, sleeve contact of jack 211, sleeve of trunk plug 295, resistance 296, normal contact and upper armature of trunk controlling relay 297, winding of trunk ringing relay 298, spring switch 299 and normal contact of said relay, waiting interrupter 300 and grounded battery 293 completing the circuit to ground.

If the connection has been made to a busy line, trunk ringing relay 298 is only partially energized in the manner that has been heretofore described. The lowermost one of the two top armature switches of relay 298 engages its two contacts, the engagement with its right hand contact energizing trunk controlling relay 297 which remains energized as long as trunk plug 295 is engaged with a jack on account of the current flowing in its lower winding.

If the connection has been made to an idle line, trunk ringing relay 298 is fully energized and all its respective armature and spring switches engage or disengage their respective contacts.

Previous to the response of the called substation, whether the connection be a waiting one or not, if the calling party replaces his receiver upon its switchhook, trunk relay 290 is deenergized and its armature switch engages its normal contact. As said armature switch is connected to grounded battery 293 and its normal contact connected to the left hand contact of the lowermost one of the two top armature switches of trunk ringing relay 298, which is engaged with its armature switch, the upper winding of trunk controlling relay 297 and the winding of trunk ringing relay 298 are short circuited and trunk ringing relay 298 is therefore deenergized, the lowermost one of its two top armature switches disengage its right hand contact first and then its left back contact thereby removing the short circuit made when the armature switch of trunk relay 290 engages its normal contact. As said disengagement with the right hand contact has already opened the circuit through the winding of said relay and as controlling relay 297 remains energized due to the current flowing in its lower winding, trunk ringing relay 298 cannot again be energized until calling plug 295 is removed from the jack, thereby deenergizing the trunk controlling relay 297. The deenergization of the trunk ringing relay 298 restores the called for line to its normally idle condition, allowing the same to test idle at all its associated multiple contacts and restoring the control of the line signal to the substation associated with said line.

When trunk ringing relay 298 is fully energized ringing current is impressed upon the line around the winding of trunk supervisory relay 301 from constant ringing interrupter 302 and intermittent battery current is impressed on the line from said winding through battery interrupter 303 in the same way as hereinbefore described in relation to Fig. 1. No interrupter to produce periodic ringing is shown in Fig. 5, though one may be used as also may be used any of the various forms of party line ringing illustrated in Fig. 1.

The return path for the ringing current to the grounded terminal of alternating current ringing generator 304 is through the ring contact of trunk plug 295, uppermost one and engaged contact of the two top armatures of trunk ringing relay 298, ring spring of trunk jack 289 at the A board and thence to ground through the repeating coil associated with the link connector engaged with said trunk jack. As said contact and armature of trunk ringing relay 298 are not engaged when waiting connection is made, the calling party does not receive an audible ringing signal until the call bell has actually been rung.

When the called party responds trunk supervisory relay 301 actuates as heretofore described in the previous cases. The engagement of its armature with its alternate contact closes a circuit through trunk calling relay 292 which may be traced as follows: from ground, through the cut-off relay and sleeve contact of trunk plug 295, alternate contact and engaged armature of trunk supervisory relay 301, winding of trunk calling relay 292 and grounded battery 293, completing the circuit to ground. 65 70 75

Trunk calling relay 292 is shown diagrammatically in Fig. 5 as performing its functions in a certain sequence; while this illustrated and described sequence of operative functions is not obligatory, I prefer its form on account of the absolute assurance it offers that the change from the described ringing connections to the described talking connections will always be 80 carried out in the proper way. As said sequence of operations does not rely on any adjusting means, frequent use of the relay and the consequent wearing away of its contacts and moving members cannot effect 85 said sequence. Also, battery commutator 303 impresses an intermittent direct current on the circuit including the winding of direct supervisory relay 301; while this relay can readily be made to maintain its armature switch engaged over its alternate contact, without vibrating, when its winding is energized by this intermittent direct current on account of the great rapidity of the pulsation of said current, to do so entails a 90 95 100 105

comparatively large core for the electromagnet or a comparatively large armature or both. As this destroys to a great extent the rapidity of action of said relay which is most desirable in a supervisory relay, I prefer to use a means similar to the one illustrated in Fig. 5 as in that case trunk supervisory relay 301 may be the same class of sensitive relay now used for supervisory purposes and which is well known in the art. It will be readily understood that calling relay 39 illustrated in Fig. 1 can be similarly arranged as its connections are similar in character. 110 115 120 125

When trunk supervisory relay 301 actuates, its armature switch may or may not rapidly engage and disengage its alternate contact, due to the intermittent current from battery interrupter 303 flowing through its winding, it being immaterial as far as the actuation of trunk calling relay 292 is concerned, whether such vibration takes place or not. Trunk calling relay 292 is so arranged that its bottom armature switch moves with the greatest freedom, without necessarily incurring any movement of the other armature switch of the various spring switches. Therefore, if the

armature switch of trunk supervisory relay 301 vibrates, momentarily closing and opening the circuit through the winding of trunk calling relay 292, a consequent intermediate 5 energization of the latter is sufficient to start said bottom armature switch vibrating. The great freedom with which said armature switch moves enables it to engage spring switch 305 if not with the first of said vibrations then after having vibrated a few 10 times. As said trunk calling relay armature switch is connected to the armature switch of the trunk supervisory relay 301 and said spring switch 305 connected to its alternate contact, a bridged circuit is formed 15 around the vibrating armature switch of trunk supervisory relay 301 and, therefore, the winding of trunk calling relay 292 receives a constant current instead of an intermittent one. This constant current causes 20 its top armature switch to engage spring switch 291 and then to disengage the same from its normal contact, and its bottom armature switch to continue its actuation. 25 The movement of spring switch 305 causes the lowermost one of the various spring switches to close a circuit from grounded battery 293, through talking supervisory lamp or signal 306, the energization of the latter always indicating to the operator 30 that the trunk link connector is being used for conversational purposes. The operation of the remaining spring switches takes place in sequence as follows: first, the normal contact 35 of the middle one of the three bottom armature switches of trunk ringing relay 298 is connected to the live pole of grounded battery 293 through the winding 307 of the repeating coil; second, the ring contact of trunk plug 295 is connected to ground through winding 308 of the repeating coil; third and last, spring switch 309 disengages its contact. The first and second described actions may be reversed or 40 so arranged as to be performed simultaneously, the only purpose in the sequence of operations being to insure the making of the connections to windings 307 and 308 of the repeating coil previous to the disengagement of spring switch 309 from its contact. 45

The described actuation of the top armature switch of trunk calling relay 292 has changed the circuit connections at the B 55 board between the tip and ring limbs of the trunk line, said circuit may now be traced as follows: from the tip spring of trunk jack 289, lower winding of trunk relay 290, spring switch 291 of trunk calling relay 292 and engaged armature switch and windings 60 310 and 311 of the repeating coil, completing the circuit through the ring spring of trunk jack 289 and the link connector apparatus associated therewith. 65 The upper high resistance winding of

trunk relay 290 is disconnected from said tip spring when said armature disengages spring switch 291 therefrom and the connection of the series windings 310 and 311 of the repeating coil to said tip and ring 70 springs furnishes a low resistance path which causes the actuation of the calling supervisory relay and calling relays associated with the link connector at the A board which is connected to said springs. 75

The disengagement of spring switch 309 of trunk calling relay 292 from its contact, opens the circuit through the upper winding of trunk controlling relay 297 and trunk ringing relay 298, the former remaining energized due to the current flowing in its lower winding and the latter being deenergized. The return to normal condition of the two bottom armature switches of the latter relay disconnects the ringing current from the tip contact of trunk plug 293 and connects said contact to winding 307 of the repeating coil through the spring switch contact already made by the actuation of the trunk calling relay 292. The connection from the winding of trunk supervisory relay 301 has been changed in the same manner as hereinbefore described. As the lower low resistance winding of trunk relay 290 is bridged by condenser 312 and as the tip and ring springs of trunk jack 289 are connected through windings 310 and 311 of the repeating coil and the tip and ring contacts of trunk plug 295 are connected to windings 307 and 308 of the same, conversation can take place between the calling and called subscribers. 95

When the called substation telephone receiver is replaced upon its switchhook, the winding of trunk calling relay 292 is short circuited by the engagement of the armature of trunk supervisory relay 301 with its normal contact, due to the deenergization of said relay. The consequent deenergization of said trunk calling relay and the disengagement of its top armature from spring switch 291, connects the high resistance upper winding of trunk relay 290 to the ring spring of trunk jack 289 and disconnects the low resistance windings 310 and 311 of the repeating coil from the same. Consequently, the calling supervisory relay of the link connector engaged with said jack at the A board is deenergized and the link 100 connector and trunk line release in the hereinbefore described manner. The called line is restored to its normal idle condition in the same manner as has been hereinbefore described. 115

As trunk controlling relay 297 remains actuated the continued disengagement of its lower armature from its normal contact prevents the connection of the tip contact of trunk plug 295 to busy test primary 313 of 120 125 130

the operator's induction coil and the disengagement of the top armature switch prevents trunk ringing relay 298 from again being actuated as has been hereinbefore described.

Fig. 5 as described and illustrated may be arranged for the ringing apparatus to be located at the exchange wherein the B board is installed and may then be modified 10 according to the showing in Fig. 6 and consequently, if the party line ringing was used (the trunk circuit being modified accordingly as illustrated in Fig. 1), the B operator would have to manipulate party line 15 keys. If it, therefore, is desired to use the trunk circuit of Fig. 5, but with A board control of the ringing then the desired result can be accomplished by merely changing 20 the connection from the alternate contact of the middle one of the three bottom armatures of trunk ringing relay 298 as shown in Fig. 6 by line 314 and the connection from the lowermost one of said armature switches as shown in Fig. 6 by line 25 315 to a connection to battery interrupter 91 as illustrated in this figure as well as in Fig. 1 where it is located at the telephone exchange where the A board is installed. When these changes are made whatever 30 class of ringing current was impressed upon the tip and ring springs of trunk jack 289 by the A operator would operate the call bell at the desired substation, the ringing current passing from said tip spring 35 to said alternate contact of trunk ringing relay 298 instead of from ringing interrupter 302. The change of the other connection from intermediate armature 303 to a connection to the same interrupter at the 40 other exchange is made because it is essential for the operation of the disclosed system of automatic ringing that the intermittent direct current be impressed upon the called substation line through the winding of trunk supervisory relay 301 in exact 45 synchronism with the intervals between the impression of the alternating or pulsating current as the case may be, from the interrupters connected direct to the ringing generator. If the ringing generator interrupter was located at one exchange and the battery interrupter was located at the other, such synchronism would be difficult to obtain, though it might be accomplished 55 if desired. Therefore, as it is much simpler and only requires one wire between two exchanges, I prefer the change as indicated by line 315, as absolute synchronism is obtained thereby between the functions of the 60 alternating and direct current interrupters, inasmuch as the same are mounted on the same shaft and are so connected as to resolve uniformly. As the circuit for the intermittent direct current is closed through 65 the winding of trunk supervisory relay 301

for a very brief interval representing the time needed to energize said relay first, then energize trunk calling relay 292 and then deenergize trunk ringing relay 298, the amount of current that will flow through 70 line 315 at any one time is exceedingly small as in practice but few trunk supervisory relays will actuate it precisely the same time. Therefore, said line which connects the two exchanges can be common to 75 all the trunk circuits at the B board which originate at the same exchange and need not be of large current carrying capacity, not alone for the reason detailed above, but on account of the fact that trunk supervisory relay 301 actuates with a small amount of current, due to the fact that the non-inductive resistance 316 is not bridged 80 across its winding until after trunk calling relay 292 has fully actuated. 85

What is claimed is:

1. In a telephone system, a calling line, a called line, stations for each of said lines, an operator's cord circuit and a trunk circuit for interconnecting said lines, said trunk circuit comprising in part a common path for talking and ringing purposes and in part separate paths for each of these two purposes, means for applying ringing current to the called line over the two parts of the ringing path, and means responsive to the restoration of the calling line for disassociating the ringing current from the called line and for establishing an electrical condition in the trunk circuit and the called line indicating a non-busy condition and without disabling the ringing paths to permit a recall of said called line over said ringing paths. 95

2. The combination in a telephone system of line wires leading from a central office to subscriber's stations, a cord circuit and a trunk circuit for establishing a connection between a calling and a called one of said stations, a trunk circuit having a portion common for both ringing and telephone conversation and another portion divided into two parts, one for ringing and the other for telephone conversation, a source of ringing current, means for connecting current from said source to the called line over the ringing paths, means controlled over a part of the trunk circuit by one of the subscribers and over a part of the cord circuit and the trunk circuit by another of the subscribers for disconnecting the ringing current from the called line, and means actuated by the calling subscriber for establishing an electrical condition in the trunk circuit and the called line indicating a non-busy condition without disabling the ringing paths to permit a recall of said called line over said ringing paths. 115

3. A telephone exchange system including telephone lines extending from substa- 130

- tions having calling signal apparatus to an exchange, an answering switchboard and a trunking switchboard, means for connecting said switchboards comprising a cord circuit at said answering switchboard, a source of signaling current associated with said cord circuit at said answering switchboard, a trunk circuit at said trunking switchboard to connect to a called substation, means to impress signaling current from said source over said cord circuit and trunk circuit upon the line of said substation to actuate said calling signal apparatus, and means under control of apparatus at a calling substation connected to said cord circuit at said answering switchboard to discontinue said impression of signaling current from the cord circuit but maintaining the trunk circuit portion of the ringing current path complete.
4. In a telephone system, a calling subscriber's line, a called subscriber's line, an operator's cord circuit and a trunk circuit for manually connecting said lines, means in the cord circuit and trunk circuit operating to apply a busy potential on the called subscriber's line when said lines are connected, means controlled by the calling subscriber's line for removing said busy potential without taking down the manual connection, means for signaling the called subscriber over a normally maintained path in the trunk circuit, a relay in the trunk circuit for establishing a separate telephonic path if the called subscriber has answered the signal and for maintaining said path complete after the busy condition has been removed and means for preventing the relay from establishing this telephonic path and for maintaining the signaling path complete if a called subscriber has not answered when the busy condition is removed.
5. In a telephone system, a calling subscriber's line, a called subscriber's line, a cord circuit and a trunk circuit for connecting these lines, said trunk circuit having two paths, one for signaling purposes and another for telephone conversation, means for applying ringing current automatically to the called subscriber's line over the signal path established when said lines are first connected, means for establishing a busy potential on the called subscriber's line when said lines are connected, means for disabling said busy potential and simultaneously removing the ringing current from the line without establishing the path for telephone conversation if the called subscriber has not answered the call, means for establishing said path for telephone conversation and removing the ringing current when the called subscriber answers and means for disabling said busy potential and maintaining the path for the telephone conversation through the trunk circuit complete after the called subscriber has answered the call.
- In witness whereof, I hereunto subscribe my name this 31st day of January A. D., 1923.

HUBERT S. TURNER.
